APPARATUS FOR PRESSING CLOTHING

Sam H. MacFarland, Evanston, Ill.

Application July 7, 1934, Serial No. 734,139

19 Claims. (Cl. 100—57)

My invention relates to apparatus for pressing clothing and more particularly to such apparatus for special use in pressing trousers and the like without the application of heat.

As is well known, unless trousers are pressed at very frequent intervals they soon become loose and baggy in appearance, much to the detriment of the wearer. Due to the trouble and expense it is not feasible to send one's trousers to the tailor or pressing establishment every day, but if the owner of the trousers possessed a pressing device of the nature herein described the trousers could be very easily and quickly inserted in this pressing device at night before the wearer retires and removed in the morning, thus keeping the trousers in pressed condition every day.

Among the objects of this invention is to provide a home pressing device requiring no heat but built sufficiently strong and rigid that a pair of trousers or other article of wearing apparel can be placed therein at night and removed nicely pressed in the morning.

Another object is to provide such pressing device that will be quickly available for use, easily manipulated and efficient in operation.

A further object is to provide a separate pressing board adapted to lie flat between the trouser legs, this pressing board having an indentation formed in one end such as to fit the curvature of the crotch of the trousers.

A still further object is to provide improved and efficient means for applying pressure to press the pressure plates toward each other for pressing the trousers therebetween.

Another object of my invention is to make possible a pair of pressing plates hinged together along one edge and having pressure applying means which may after the pressing operation is completed be quickly released at the non-hinged side of the plates to permit swinging the top plate upwardly from the bottom plate, and also capable of being quickly attached for pressure applying purposes when the top plate is swung down against the bottom plate or against a pair of trousers therebetween.

A further object is to provide a pressing device having improved means for adjusting the amount of pressure to be applied to said device.

Other objects, advantages and capabilities will later become more readily apparent.

My invention further resides in the combination, construction and arrangement of parts illustrated in the accompanying drawings, and while I have shown therein a preferred embodiment I wish it understood that the same is sus-

ceptible of modification and change without departing from the spirit of my invention.

Referring to the drawings:—

Fig. 1 is a perspective view of my improved pressing device with the hinged pressing plates open and a pair of trousers in position to be applied between the pressing plates but shown for sake of clearness to one side of the device.

Fig. 2 is a top plan view of my improved device showing a pair of trousers being pressed therein.

Fig. 3 is a fragmentary top plan view partly broken away of that portion of the pressing device carrying one of the pressure applying mechanisms.

Fig. 4 is a sectional view taken on the line 15 4—4 of Fig. 3.

Fig. 5 is an edge view on the line 5—5 of Fig. 3 looking in the direction of the arrows.

Fig. 6 is a sectional view taken on the line 6—6 20 of Fig. 3.

Fig. 7 is a section taken on the line 7—7 of Fig. 3.

Fig. 8 is a sectional view taken on the line 8—8 25 of Fig. 3.

Fig. 9 is a view similar to Fig. 6 but showing the operating lever thrown to the opposite position from Fig. 6 so as to loosen the pressure between the pressing plates.

Fig. 10 is a view similar to Fig. 8 but showing 30 the operating lever thrown from tightening position to loosening position to loosen the pressure between the pressing plates.

Fig. 11 is a sectional detail showing the means for holding the pressure applying shaft against 35 accidental rotation.

Fig. 12 is a vertical transverse section through a pressing device embodying my invention and taken approximately on a plane closely adjacent one of the rotatable operating shafts.

Referring more in detail to the drawings, my improved device is shown in Fig. 1 to comprise the bottom plate and the top plate 2 hinged thereto along one edge by a pair of hinges indicated generally at 3. Each of the bottom and

top plates 1 and 2 are preferably covered by any suitable fabric 4 and 5 such as linen or the like, this fabric being preferably glued to the faces of the respective plates. Also in Fig. 1 slightly removed to one side is shown a pair of trousers

6 in position to be inserted into the pressing device. To facilitate the pressing of the trousers I preferably use a pressing board B made of any suitable material and likewise covered with linen or other suitable fabric and adapted to be placed flatwise between the two legs of the pair of

trousers. This pressing board is formed at one end with an indentation C of such shape as to fit the curvature of the crotch of the trousers.

Assuming the trousers to be arranged as shown 5 slightly removed to the right from the pressing plates in Fig. 1, they will be placed upon the bottom plate 1 and the top plate 2 will then be closed down thereon and the pressure applied. Each of the plates 1 and 2 are of material sufficiently rigid to prevent deformation during the 10 pressing action. These plates may be made of wood, metal or other suitable material.

It is, of course, understood that when trousers 15 are being pressed in this device, instead of arranging them separately as shown to the right in Fig. 1, this arrangement may be effected by first laying one leg of the trousers on the bottom plate 1, and after smoothing it into the correct position then laying thereon the pressing board B with 20 the indentation C fitting around the curvature of the crotch of the trousers, and then laying and smoothing out the upper trouser leg on top of the pressing board B and then swinging the top plate 2 downwardly upon the trousers. If it is not 25 desired to press the cuffs of the trousers they may project slightly beyond the end of my pressing device, or if it is desired to press them they may be positioned slightly within the end of the pressing device so as to receive pressure.

30 The pressure applying means will now be described. Plates 1 and 2 are hinged together along one edge, this hinge comprising the flat piece of metal 7 secured by screws or the like 8 to the edge of the lower pressing plate. Hingedly connected at 3 to the upper side of this portion 7 is in upstanding ear 9. Formed in the upper end of the ear 9 is opening 10 of such irregular shape that when the eccentrically located pin 11 is moved around because of rotation of the transverse shaft 12 this pin 11 will move to the top 35 part of opening 10 and cause the top plate 2 to be pressed downwardly toward the bottom plate 1.

40 A keeper 13 is secured by screws or the like 14 to the edge of the top plate 2, this keeper having a recess 15 formed therein, in which recess the upstanding ear 9 has a longitudinal sliding movement to permit the plates 1 and 2 to move toward and away from each other under action of the pressure applying means. Fixed to the opposite 45 edges of the top plate 2 are ears 16, there being one for each end of each of the rotatable shafts 12, these ears 16 having an aperture 17 therein, in which apertures the shaft 12 is rotatably mounted. Formed or fixed in any manner desired to each end of each of the shafts 12 is a pin 11 eccentrically mounted in order to have the general action of a crank shaft when the shaft 12 is rotated. As stated above, these pins 11 on the hinge side of the pressing plates when 50 the shaft is rotated in one direction move upwardly to the top of opening 10 and then engage the top of this opening, and from then on until the pin 11 reaches its uppermost movement causes ear 9 to move upwardly through keeper 65 13, thus causing the pressing plates 1 and 2 to move toward each other. A reverse rotation of shaft 12 will release this pressure in a manner that will be readily understood.

60 Rotation of shaft 12 is effected through the medium of the hand operated handle 18 provided with a finger piece 19, this handle being fixed by a screw 20 or other suitable means to shaft 12. The collar of the handle 18, which collar surrounds shaft 12, is provided with an enlarged 65 portion 21, which has sliding movement in a

groove 22 formed in plate 23 secured to the top of the top plate 2. This enlarged portion 21 when the shaft has been rotated into tightened position as shown in Fig. 7, has more or less of a binding action in the groove 22 and tends to prevent accidental rotation of the shaft 12 out of tightened position.

Upon the free edge of lower plate 1 and directly opposite the hinge 3 is a device for releasably engaging the adjacent eccentrically located pin 11, so that when the top plate 2 is 10 swung down upon the bottom plate 1 this engagement may be effected for applying pressure to the trousers or other garment being pressed, and after such pressing action is completed may 15 be released to permit the top plate 2 to be swung upwardly away from the bottom plate 1. This arrangement of parts will now be described.

20 Adjustably fixed to the edge of the bottom plate is an upwardly extending ear 24 having 20 therein a recess 25, in which is pivotally mounted the finger 26 provided at its top with the hook portion 27 (see Figs. 8, 10 and 12). The lower end of the finger 26 is formed with an enlargement 28 which may either be pivotally mounted upon a 25 pin passing therethrough or loosely pivoted in a somewhat larger opening 29 as desired. Any connection between these parts permitting the finger 26 and hook 27 to have a lateral rocking motion may be used. Normally tending to press 30 the finger 26 toward the right as viewed in Fig. 8 is a spring 30. When the top plate 2 is swung away from the bottom plate 1 spring 30 will hold finger 26 against the shoulder 31, the free end of the hook member 27 when the finger is in this 35 position still standing far enough away from the upper right hand edge of the metal forming the recess 25 in order to provide the open throat 32, through which the eccentrically mounted crank pin 11 may pass when the top plate 2 is 40 swung downwardly against the bottom plate 1 (or against the trousers or other garment that may be positioned therebetween); or if the pin is not in exact position to freely pass through this throat 32 it will strike the beveled edge 33 45 formed at the free end of hook 27, and this beveled edge 33 acting like a cam will press the finger 26 to the left, as viewed in Fig. 8, until the pin 11 has passed underneath hook 27, at which time spring 30 will press finger 26 to the right 50 to its extreme limit.

When pin 11 is thus inserted through throat 32 to be in a position below the free end of hook 27, rotation of shaft 12 in a clockwise direction, as viewed in Fig. 8, will carry pin 11 around until it engages the hook member 27, and from then on until pin 11 reaches its uppermost movement will pull upwardly on hook 27, which in turn will transmit this upward pull to ear 24, and thus apply a clamping pressure to move 60 plates 1 and 2 toward each other to apply pressure to whatever article is positioned between the pressing plates 1 and 2.

Ear 24 is slidably mounted within a recess 34 formed in keeper 35, which is secured by screws 65 36 or the like to the edge of the top plate 2. Ear 24 is also adjustably mounted in a more or less similar keeper 37, which is secured by screws or the like 38 to the edge of the bottom plate 1. Fixed in the recess 39 of keeper 37 is the plate 70 40, in which is mounted the threaded screw 41, which has threaded engagement with ear 24, as shown at 42. Secured by screws or the like 43 to the bottom of ear 24 is a plate or shim 44, which may be applied or removed as desired for 75

the purpose of making the ear 24 occupy a higher or a lower position. As will be obvious from the above description the rotation of screw 41 will cause the ear 24 to move upwardly or downwardly for adjusting purposes to accommodate the pressing of thicker or thinner articles in the pressing device. While I have described only one of this assembly of parts associated with ear 24, it will be understood that this description 10 also applies to the similar parts located at the non-hinged end of shaft 12 for as many others of these shafts as may be used. For convenience I have shown two of these shafts 12 in the drawings, but a greater or less number may be used 15 as desired.

From the above it will be seen that when each of the shafts 12 is rotated in the appropriate direction to relieve the pressure between plates 1 and 2, the eccentric or crank pins 11 will move 20 into alignment with throat 32, after which the top plate 2 may be swung upwardly away from the bottom plate 1, the reverse movements being effected for again bringing these parts into engagement and applying pressure between the 25 plates 1 and 2.

It is also apparent that other specific forms of the parts described may be used without departing from the spirit of my invention, the broad idea being to provide parts that will apply pressure between plates 1 and 2 upon movement of the eccentric pins 11 and also permit disengagement of the parts at the non-hinged side of the pressing device to permit swinging the top plate to open position.

The pressing device described herein is such as to be quickly manipulated and apply considerable and adjustable pressure as desired to the article being pressed, which pressure may be retained as long as desired and quickly and easily 40 released when it is desired to remove the article being pressed from between the top and bottom plates 1 and 2.

Having now described my invention,

I claim:

1. In apparatus for pressing clothing, in combination, a rigid bottom plate, a rigid top plate, said plates being hinged together along one edge, an upstanding ear on one edge of the bottom plate, an upstanding ear on the opposite edge 50 of the bottom plate and opposite the first mentioned ear, a pair of keepers on the top plate through which said ears have sliding movement, and means extending across the upper surface of the top plate for simultaneously causing each 55 of said ears to slide vertically through its respective keeper to move said plates toward each other to press an article of clothing therebetween.

2. In apparatus for pressing clothing, in combination, a rigid bottom plate, a rigid top plate, said plates being hinged together along one edge, an upstanding ear on one edge of the bottom plate, an upstanding ear on the opposite edge of the bottom plate and opposite the first 60 mentioned ear, a pair of keepers on the top plate through which said ears have sliding movement, and means extending across the upper surface of the top plate for simultaneously causing each 65 of said ears to slide vertically through its respective keeper to move said plates toward each other to press an article of clothing therebetween, one of the ears forming part of the hinge for said plates.

3. In apparatus for pressing clothing, in combination, a pair of rigid plates hinged together 70

at one edge, an upstanding ear on one edge of one of said plates, an upstanding ear on the opposite edge of the last mentioned plate and opposite the first mentioned ear, a shaft rotatable about its longitudinal axis and extending across the outer face of the other plate, and means on the outer ends of said shaft cooperating with said ears whereby upon rotation of said shaft the plates will be pressed toward each other to press an article of clothing therebetween. 10

4. In apparatus for pressing clothing, in combination, a pair of rigid plates hinged together at one edge, an upstanding ear on one edge of one of said plates, an upstanding ear on the opposite edge of the last mentioned plate and opposite the first mentioned ear, a shaft rotatable about its longitudinal axis and extending across the outer face of the other plate, and means on the outer ends of said shaft cooperating with said ears whereby upon rotation of said shaft the 20 plates will be pressed toward each other to press an article of clothing therebetween, and a pair of keepers secured to the edges of said other plate, said ears being slidably through said keepers upon rotation of said shaft. 25

5. In apparatus for pressing clothing, in combination, a pair of rigid plates hinged together at one edge, one of said plates having a pair of upstanding ears, and means on the other plate cooperating with said ears for pressing said plates 30 toward each other, said means comprising a shaft rotatable about its longitudinal axis and having its opposite ends provided with off-set means engageable with the respective ears.

6. In apparatus for pressing clothing, in combination, a pair of rigid plates hinged together at one edge, one of said plates having a pair of upstanding ears, and means on the other plate cooperating with said ears for pressing said plates toward each other, said means comprising a shaft 40 rotatable about its longitudinal axis and having its opposite ends provided with offset means engageable with the respective ears, and a pair of keepers fixed to said other plate, said ears being slidably in said keepers. 45

7. In apparatus for pressing clothing, in combination, a pair of rigid plates hinged together at one edge, one of said plates having a pair of upstanding ears, and means on the other plate cooperating with said ears for pressing said plates 50 toward each other, said means comprising a shaft rotatable about its longitudinal axis and having its opposite ends provided with offset means engageable with the respective ears, a pair of keepers fixed to said other plate, said ears being slidably 55 in said keepers, and apertured ears fixed to said other plate one adjacent each of said keepers, said shaft being rotatably mounted in said last mentioned ears.

8. In apparatus for pressing clothing, in combination, a pair of rigid plates hinged together at one edge, one of said plates having a pair of upstanding ears, and means on the other plate cooperating with said ears for pressing said plates 60 toward each other, said means comprising a shaft rotatable about its longitudinal axis and having its opposite ends provided with offset means engageable with the respective ears, a pair of keepers fixed to said other plate, said ears being slidably 65 in said keepers, apertured ears fixed to said other plate one adjacent each of said keepers, said shaft being rotatably mounted in said last mentioned ears, and means on said shaft to facilitate rotating the same. 70

9. In apparatus for pressing clothing, in combination, a pair of rigid plates hinged together at one edge a rotatable shaft extending transversely across the outer face of one of said plates, and means associated with the ends of said shaft and said plates for pressing the plates toward each other upon rotation of the shaft, and means for releasing one end of said shaft from one of said plates to permit the plates to be swung open when the shaft is rotated to a predetermined position. 10
10. In apparatus for pressing clothing, in combination, a pair of rigid plates hinged together at one edge, an ear on the hinge side of one of said plates, an ear on the opposite side of the same plate, a shaft rotatably mounted on the outer face of the other plate, the ends of the shaft being formed to cooperate with said ears for pressing the plates toward each other upon rotation of the shaft in one direction, and for moving the plates 15 in a direction away from each other upon rotation of the shaft in the opposite direction, the end of the shaft and the ear on the non-hinged side of the plates being constructed and arranged to permit their separation when the shaft is rotated to a predetermined position to permit said plates to be swung open. 20
11. In apparatus for pressing clothing, in combination, a pair of rigid plates hinged together, one of said plates having a pair of upstanding ears oppositely positioned one on each edge, the other plate having a pair of keepers slidably receiving said pair of ears, said other plate also having an apertured ear slightly spaced from each keeper, a shaft rotatably mounted in said apertured ears, an eccentrically mounted pin on each end of said shaft and extending into the space between the apertured ear and the keeper, said first mentioned ears each having a portion adapted to receive and be put under tension by said eccentrically mounted pins upon rotation of said shaft. 25
12. In apparatus for pressing clothing, in combination, a pair of rigid plates hinged together, one of said plates having a pair of upstanding ears oppositely positioned one on each edge, the other plate having a pair of keepers slidably receiving said pair of ears, said other plate also having an apertured ear slightly spaced from each keeper, a shaft rotatably mounted in said apertured ears, an eccentrically mounted pin on each end of said shaft and extending into the space between the apertured ear and the keeper, said first mentioned ears each having a portion adapted to receive and be put under tension by said eccentrically mounted pins upon rotation of said shaft, one of said first mentioned ears forming part of the hinge. 30
13. In apparatus for pressing clothing, in combination, a pair of rigid plates hinged together, one of said plates having a pair of upstanding ears oppositely positioned one on each edge, the other plate having a pair of keepers slidably receiving said pair of ears, said other plate also having an apertured ear slightly spaced from each keeper, a shaft rotatably mounted in said apertured ears, an eccentrically mounted pin on each end of said shaft and extending into the space between the apertured ear and the keeper, said first mentioned ears each having a portion adapted to receive and be put under tension by said eccentrically mounted pins upon rotation of said shaft, one of said first mentioned ears forming part of the hinge, and the other of said first 35
- mentioned ears being adjustable vertically with relation to its plate. 40
14. In apparatus for pressing clothing, in combination, a pair of rigid plates hinged together at one edge, an upstanding ear on one edge of one of said plates, an upstanding ear on the opposite edge of the last mentioned plate and opposite the first mentioned ear, a shaft rotatable about its longitudinal axis and extending across the outer face of the other plate, means on the outer ends of said shaft cooperating with said ears whereby upon rotation of said shaft the plates will be pressed toward each other to press an article of clothing therebetween, and means for holding said shaft against rotation. 45
15. In apparatus for pressing clothing, in combination, a pair of rigid plates movable toward and away from each other, ears and keepers on said plates, the ears being slidable in said keepers, means for pressing one plate toward the other, one of said ears having a pivotal hook, said means having an eccentrically mounted pin for engaging said hook when applying said pressure. 50
16. In apparatus for pressing clothing, in combination, a pair of rigid plates movable toward and away from each other, ears and keepers on said plates, the ears being slidable in said keepers, means for pressing one plate toward the other, one of said ears having a pivotal hook, said means having an eccentrically mounted pin for engaging said hook when applying said pressure, and a spring for normally urging said hook in one direction. 55
17. In apparatus for pressing clothing, in combination, a pair of rigid plates movable toward and away from each other, ears and keepers on said plates, the ears being slidable in said keepers, means for pressing one plate toward the other, said means comprising a rotatable shaft rotatably mounted at each end respectively in a fixed apertured ear, each end of the shaft having an eccentrically mounted pin, one of said ears having a pivotal hook, one of said eccentrically mounted pins engaging said hook and applying clamping pressure thereto when the shaft is rotated in one direction, and being freed from said hook when the shaft is rotated in the opposite direction whereby to permit said plates to be moved apart. 60
18. In apparatus for pressing clothing, in combination, a pair of rigid plates movable toward and away from each other, ears and keepers on said plates, the ears being slidable in said keepers, means for pressing one plate toward the other, said means comprising a rotatable shaft rotatably mounted at each end respectively in a fixed apertured ear, each end of the shaft having an eccentrically mounted pin, one of said ears having a pivotal hook, one of said eccentrically mounted pins engaging said hook and applying clamping pressure thereto when the shaft is rotated in one direction, and being freed from said hook when the shaft is rotated in the opposite direction whereby to permit said plates to be moved apart, and a handle to facilitate rotating said shaft. 65
19. In apparatus for pressing clothing, in combination, a pair of rigid plates movable toward and away from each other, ears and keepers on said plates, the ears being slidable in said keepers, means for pressing one plate toward the other, said means comprising a rotatable shaft rotatably mounted at each end respectively in a 70

fixed apertured ear, each end of the shaft having an eccentrically mounted pin, one of said ears having a pivotal hook, one of said eccentrically mounted pins engaging said hook and applying 5 clamping pressure thereto when the shaft is rotated in one direction, and being freed from said hook when the shaft is rotated in the opposite

direction whereby to permit said plates to be moved apart, and a handle to facilitate rotating said shaft, one of said ears being hinged to its plate, and the other of said ears being vertically adjustable.

SAM H. MACFARLAND.
